UNITED STATES PATENT OFFICE.

HENRY OLDENDORPH, OF BELLEVILLE, ILLINOIS, AND WALTER M. OLDENDORPH, OF ST. LOUIS, MISSOURI.

PLOW.

1,067,268.

Specification of Letters Patent.

Patented July 15, 1913.

Application filed October 13, 1911. Serial No. 654,827.

To all whom it may concern:

Be it known that we, HENRY OLDENDORPH, a citizen of the United States, residing at Belleville, in the county of St. Clair, State 5 of Illinois, and WALTER M. OLDENDORPH, a citizen of the United States, residing at the city of St. Louis, in the State of Missouri, have jointly invented certain new and useful Improvements in Plows, of which the 10 following is a specification containing a full, clear, and exact description, reference being had to the accompanying drawings, forming a part hereof.

Our invention relates to improvements in 15 plows, and has for its object to provide a plow with a point having a cutting blade capable of longitudinal adjustment, to the end of enabling the cutting extremity to be renewed when the same has been reduced 20 through wear.

In the drawings Figure 1 is a side elevation of a plow point embodying our invention. Fig. 2 is a bottom plan view of the plow-share and its adjacent parts. Fig. 3 25 is a vertical sectional view taken on the line 3-3 of Fig. 2. Fig. 4 is a perspective view of the share- and landside-support. Fig. 5 is a perspective view of the frog. Fig. 6 is a perspective view of the cutter blade frame. Fig. 7 is a perspective view of the wedge 30 employed to hold the cutter blade in place within the frame. Fig. 8 is a perspective view of the cutter blade. Fig. 9 is a perspective view of the lock employed in holding 35 the cutter blade frame in position. Fig. 10 is a longitudinal sectional view of the cutter blade, showing the adjacent parts whereby it is carried.

In the drawings the plow share 11 is 40 shown provided on its rear face with yokes 12-12, the yokes 12-12 being slotted as indicated by the numeral 13 to receive the bolts 14, which bolts 14 in turn pass through the slots 15 in the support 17, at the lower edge of the mold board 16. By this means the share 11 is provided with capacity for vertical adjustment. The share- and landside-support 17 is provided with a pocket 18 adapted to receive the cutter blade frame 19 (see Fig. 6).

The cutter blade 20 is adapted to fit within the frame 19, and its slots 21 are adapted to successively engage with the lug 22. On its front extremity the frame 19 is provided

with the upwardly extending wings 23, 55 which are adapted to receive the bar 24, which terminates in the wedge-point 25, and is adapted to be seated on the upper face of cutter blade 20. Beneath the support 17 we provide the frog 26 upon whose vertical 60 face 27 the landside 28 is secured by bolts 29-29, the inclined upper surface 30 serving as a base for the support 17. The frame 19 is secured beneath the support 17 by the bolt 31 passing through the slot 32 or slot 65 33; the locking bar 34 being also held by said bolt 31, which passes through the opening 35. The locking bar 34 has the lug 36 adapted to engage with the depression 37, to secure the frame 19 against longitudinal 70 movement.

By the forward adjustment of the cutter-blade 20, when its tip has become worn in use, the plow is provided with a sharp cutting point, and such adjustment can be repeated until the end of the cutter blade is consumed through wear; when a new blade is substituted at low cost. 75

Having thus described our invention what we claim as new, and desire to have secured 80 to us by the grant of Letters Patent, is—

1. In a plow, the combination of a plow point comprising a frame, a cutter blade longitudinally and slidably mounted in said frame, and means for locking said cutter blade in place within the frame; an integral share- and landside-support having a pocket to receive said frame; a landside bar; and a frog mounted in said support and forming a base for said landside bar, 85 substantially as described.

2. In a plow, a structure adapted to form the extremity of the landside and share, and comprising a frame having a longitudinal pocket, open on its upper side, a cutter blade 95 longitudinally and slidably mounted in said pocket, a wedge shaped locking-blade adapted to fill said pocket above the cutter blade, and locking means carried by the frame to lock said cutter blade in position, substantially as described. 100

3. In a plow, the combination of a structure comprising a frame, a cutter blade longitudinally and slidably mounted in said frame, and means for locking said cutter 105 blade in place within the frame; an integral share- and landside-support having a pocket to receive said frame; a landside bar; a

frog mounted in said support and forming a base for said landside bar; and a share blade provided with upwardly projecting brackets upon its rear side, and means for 5 adjustably securing said blade and brackets to said share- and landside-support, substantially as described.

In testimony whereof, we have signed our

names to this specification, in presence of two subscribing witnesses.

HENRY OLDENDORPH.
WALTER M. OLDENDORPH.
